DECANTER

Ernest L. Du Pree, New York, N.Y., assignor to
Schenley Industries, Inc., New York, N.Y., a cor-
poration of Delaware

Filed Jan. 7, 1963, Ser. No. 73,063

Term of patent 14 years

(Cl. D58—8)

Des. 200,222

PAGE 2

FIGURE 1 is a front elevational view of a decanter embodying my new design;

FIGURE 2 is a rear elevational view thereof;

FIGURE 3 is a side elevational view of the same;

FIGURE 4 is a top plan view of the decanter as shown in FIGURE 1, the pattern shown in the latter figure being omitted for purposes of illustration;

FIGURE 5 is a vertical sectional view, as seen on the line 5—5 of FIGURE 1;

FIGURE 6 is a horizontal sectional view as seen on the line 6—6 of FIGURE 1; and

FIGURE 7 is a horizontal sectional view as seen on the line 7—7 of FIGURE 2.

I claim:

The ornamental design for a decanter, as shown and described.
